US00D807679S

(12) **United States Design Patent** (10) Patent No.: **US D807,679 S**
(45) Date of Patent: ** Jan. 16, 2018

(54) **PAN**

(71) Applicants: **TRISTAR PRODUCTS, INC.**,
Fairfield, NJ (US); **KE M.O. HOUSE
CO., LTD.**, Shenzhen (CN)

(72) Inventors: **Keith Mirchandani**, Fairfield, NJ (US);
Mo-Tsan Tsai, Shenzhen (CN)

(73) Assignees: **Tristar Products, Inc.**, Fairfield, NJ
(US); **KE M.O. House Co., Ltd.**,
Shenzhen (CN)

(**) Term: **15 Years**

(21) Appl. No.: **29/589,554**

(22) Filed: **Jan. 3, 2017**

Related U.S. Application Data

(63) Continuation of application No. 29/552,601, filed on
Jan. 24, 2016, now Pat. No. Des. 778,103, which is a
continuation-in-part of application No. 29/547,842,
filed on Dec. 8, 2015.

(30) **Foreign Application Priority Data**

Dec. 1, 2015 (CN) 2015 3 0493868

(57) **CLAIM**

The ornamental design for a pan, as shown and described.

DESCRIPTION

FIG. 1 is a perspective view of the pan;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a right side view of the pan of FIG. 1 positioned

over a gas stove burner, which is shown in broken lines.
The elements depicted in broken lines in the various figures
are included for environmental purposes only, and form no
part of the claimed design.

1 Claim, 8 Drawing Sheets
